CLAIM

The ornamental design for a combined tape cassette and label card, as shown and described.

DESCRIPTION

FIG. 1 is an exploded view of a combined tape cassette and label card showing our new design;
FIG. 2 is a top plan view of the combined tape cassette and label card;
FIG. 3 is a bottom plan view thereof;
FIG. 4 is a front elevational view thereof;
FIG. 5 is a rear elevational view thereof; and,
FIG. 6 is a right side elevational view thereof, the left side being a mirror image thereof.

FIG. 1***FIG. 2******FIG. 3******FIG. 4******FIG. 5******FIG. 6***
